Proprietor:

John J. Didcoct

UNITED STATES PATENT OFFICE.

JOHN J. DIDCOCT, OF STREATOR, ILLINOIS.

DESIGN FOR A BADGE OR SIMILAR ARTICLE.

40,709.

Specification for Design.

Patented May 31, 1910.

Application filed January 6, 1910. Serial No. 536,774. Term of patent 3½ years.

To all whom it may concern:

Be it known that I, JOHN J. DIDCOCT, a citizen of the United States, residing at Streator, in the county of LaSalle and State of Illinois, have invented a new, original, and ornamental Design for a Badge or Similar Article, of which the following is a specification, reference being had to the accompanying drawing, forming a part thereof.

The figure is a plan view of a badge or similar article showing my new design.

I claim:

The ornamental design for a badge or similar article as shown.

JOHN J. DIDCOCT.
